UNITED STATES PATENT OFFICE.

FRANK H. THOMPSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

TACK-PULLING MACHINE.

1,374,250.

Specification of Letters Patent. Patented Apr. 12, 1921.

Application filed June 11, 1919. Serial No. 303,293.

To all whom it may concern:

Be it known that I, FRANK H. THOMPSON, a citizen of the United States, residing at Beverly, in the county of Essex and State 5 of Massachusetts, have invented certain new and useful Improvements in Tack-Pulling Machines; and I do hereby declare the following to be a full, clear, and exact description of the invention, such as will enable others skilled in the art to which it 10 appertains to make and use the same.

The invention relates to tack pulling machines, and more particularly to that type of machine in which the tack is pulled by 15 a pair of reciprocating jaws which engage opposite sides of the tack.

In the machine embodying the invention, the tack pulling jaws are secured or formed on the free ends of a pair of jaw carrying 20 levers, which are pivoted to a pair of swinging links and are connected at their other ends with two oppositely rotating cranks. This affords a simple and compact mechanism for giving the jaws the proper tack 25 engaging and pulling movements, which is well adapted for operation at the highest speed consistent with the proper operation on the tacks. It also enables the jaw to be closed upon the tack while moving at comparatively low speed and to pull the tack 30 while moving at comparatively high speed.

The invention will be readily understood from an inspection of the accompanying drawing and the following detailed description 35 of the mechanism described therein.

In the drawing, the mechanism embodying the invention in its preferred form is shown in elevation.

In the machine shown in the drawing, 40 the tack pulling jaws 2 are formed on the lower or free ends of two jaw carrying levers 4 which are oppositely curved and cross one another immediately above the jaws. The levers are connected immediately 45 above the crossing point to two oppositely swinging links 6 which are mounted on the supporting head 8. The upper ends of the jaw carrying levers are connected to crank pins 10 carried by two oppositely rotating 50 and intermeshing gears 12.

Work supporting plates 14 are arranged to underlie the jaws 2 and are spaced to provide a slot in which the tacks may be positioned when the shoe is held against

the work supporting plates, as indicated in 55 the drawing.

The jaw carrying levers, links and cranks are so arranged that the tack pulling jaws are given the path of movement indicated by the dotted lines in the drawing. The 60 jaws move toward each other to engage a tack when they are close to the work supporting plates and when the cranks are moving in a substantially horizontal direction so that the jaws will have at this time 65 a speed about one third that of the cranks. After the jaws have engaged the tack, they move in vertical parallel paths while the cranks are moving vertically so that at this time they have substantially the same speed 70 as the cranks. They are then separated to release and discharge the tack, after which they are returned to position close to the work supporting plates and again brought together to engage a tack positioned between 75 them.

What is claimed is:

1. A tack pulling machine, comprising a pair of levers, oppositely rotating cranks connected to the ends of the levers, a tack 80 pulling jaw supported upon the opposite end of each lever and a swinging link connected to each lever intermediate its ends.

2. A tack pulling machine, comprising a pair of levers, a crank connected to one end 85 of each lever, means for rotating the cranks in opposite directions at the same speed, a jaw supported upon the opposite end of each lever and a swinging link connected to each lever intermediate its ends. 90

3. A tack pulling machine, comprising a pair of levers, a rotary crank connected to one end of each lever, means for rotating the cranks in opposite directions, a swinging link supporting each lever intermediate its ends, and a tack pulling jaw supported upon the free end of each lever, the jaws being constructed and arranged to move in substantially parallel paths to pull the tack. 95

4. A tack pulling machine, comprising a pair of opposed tack pulling jaws and means for actuating the jaws to first engage with opposite sides of the tack, to next move in parallel paths to pull the tack and finally to separate to disengage the tack, and mechanism for moving the jaws in the above described paths consisting of jaw carrying levers, oppositely rotating cranks connected 100

to the adjacent ends of the levers and swinging links connected to the levers intermediate their ends.

5. A tack pulling machine, comprising a pair of jaw carrying levers which cross one another adjacent the free ends, a rotary crank connected to the opposite end of each lever and a swinging link connected to each lever between the rotary crank and the 10 crossing point of the levers.

6. A tack pulling machine, comprising a pair of work engaging members adapted to receive the tack between them, a pair of levers, a tack pulling jaw carried upon the free end of each lever, a crank connected to the opposite end of each lever, means for rotating the cranks in opposite directions and an oscillatory link connected to each lever intermediate its ends. 15

FRANK H. THOMPSON.
